UNITED STATES PATENT OFFICE.

SARAH QUEE, OF PASADENA, CALIFORNIA.

MATCH-SAFE.

SPECIFICATION forming part of Letters Patent No. 758,215, dated April 26, 1904.

Application filed January 22, 1904. Serial No. 190,225. (No model.)

To all whom it may concern:

Be it known that I, SARAH QUEE, a citizen of the United States, residing at Pasadena, in the county of Los Angeles and State of California, have invented new and useful Improvements in Match-Safes, of which the following is a specification.

My invention relates to a receptacle primarily designed for holding matches for use with a gas-range; and the object thereof is to provide a convenient receptacle which may be detachably secured to the top of the gas-range, which receptacle is provided with two compartments, one for holding the burned matches and the other for holding the match before it is lighted, and also to provide convenient means whereby the match can be readily ignited.

In the use of gas-ranges it is necessary that the different burners thereof be frequently lighted, and unless the receptacle which holds the matches is very accessible to the burner many steps are taken in order to obtain the matches necessary to light the burners. After the matches are burned usually there is no convenient receptacle to put the burned matches in, and they are laid on the top of the range or thrown upon the floor, and in either case they form an objectionable feature when disposed of in that manner. Again, there is no convenient place on which to strike the match to light it. Frequently the top of the range is used, and if the same should be greasy, as frequently happens in cooking, the match will not light thereon, but will be destroyed. With my improved match-safe, which is illustrated in the accompanying drawings, these difficulties are avoided.

In the drawings, Figure 1 is a perspective view of a fragment of a top of a gas-range with my improved match-safe attached thereto. Fig. 2 is a perspective view of a match-safe detached from the range.

In the drawings, A is the top of a gas-range, and B is my improved match-safe secured thereon. This safe consists of a small compartment B', which is designed to hold the unburned matches, and the larger compartment B'', designed for holding the burned matches. Near the center of the top of the larger com-

partment is secured an arm C, the top of which is roughened, as shown at C', to form a surface upon which the matches may be scratched to light them. This arm is turned at right angles to the main body thereof to pass through the apertures A' of the gas-stove and is provided with side pieces C'', which may be either rigidly or pivotally secured thereto. These side pieces are designed to project underneath the top of the range to prevent the accidental displacement of the match-safe therefrom. Where the apertures in the top of the range are sufficiently large to permit of rigid side pieces being used, I prefer to make the side pieces rigid; but where the apertures are small, as sometimes happens, the side pieces must be pivotally connected to the arm, so that they may be folded together to pass into the aperture and then spread out. As the receptacle for the burned matches is intermediate the range and the receptacle for the unburned matches, there is no danger of the unburned matches catching fire.

These match-safes are preferably constructed of metal, tin being preferred. By this construction a cheap, efficient, and convenient receptacle is provided for holding both the burned and unburned matches and providing a convenient means to light the match.

Having described my invention, what I claim as new, and desire to secure by Letters Patent, is—

1. A match-safe divided into two compartments; an arm secured to one of said compartments, said arm having the exposed portion thereof roughened and having side pieces secured upon the end thereof.

2. A match-safe divided into two compartments; an arm secured to one of said compartments, said arm having means for detachably securing said safe to a gas-range, said arm also having an igniting-surface upon which a match may be caused to ignite.

In witness that I claim the foregoing I have hereunto subscribed my name this 15th day of January, 1904.

SARAH QUEE.
